ELECTRIC FEELER MECHANISM FOR LOOMS

Filed Aug. 1, 1933

UNITED STATES PATENT OFFICE

1,993,492

ELECTRIC FEELER MECHANISM FOR
LOOMS

Richard Greenleaf Turner, Worcester, Mass., assignor to Crompton & Knowles Loom Works, Worcester, Mass., a corporation of Massachusetts

Application August 1, 1933, Serial No. 683,138

13 Claims. (Cl. 139—273)

This is a continuation in part of my prior copending application Serial No. 653,642, and relates to electrical weft detectors for looms. It is the general object of the invention to provide mechanism of this type which shall avoid repeated contacts with the weft and at the same time retain positiveness of indication.

In the aforesaid application I have shown a shuttle with an internal weft detector cooperating with a contacting plate normally held below contacting position in the shuttle by presence of sufficient weft. Upon exhaustion of weft the contact plate rises to indicating position where it is preferably locked to resist pressure of the contacts. It is an important object of my present invention to provide contacts which engage the plate when the latter is in indicating position.

When the contacts are in the form of rolls it is desirable to prevent improper contact between them and the plate if sufficient weft is present. This may be accomplished by forming the rolls preferably with hubs of sufficient diameter to keep the contacting rims away from the depressed plate. This latter provision is rendered desirable by the fact that the contact plate is at all times exposed and could therefore give an indication whenever the rolls contacted with it, in this respect being different from those forms of contacts which are carried by bobbins and covered by the yarn which serves as insulating material.

The constant wearing of the picker will ordinarily result in the shuttle being boxed nearer and nearer the end of the lay, the effect of which is to carry the contact plate out of the range of the rolls. It is a further object of my invention to provide means for giving the rolls a plurality of positions depending upon the wearing of the picker so that proper registry may always be attained. The brushes which contact with the rolls may be of sufficient length to cover all positions of the roll axis.

With these and other objects in view which will appear as the description proceeds, my invention resides in the combination and arrangement of parts hereinafter described and set forth in the claims.

In the accompanying drawing, wherein a convenient embodiment of my invention is set forth,

Fig. 1 is a top plan view of the plain end of a loom lay having my invention applied thereto.

Fig. 2 is a detailed longitudinal section on line 2—2 of Fig. 1.

Fig. 3 is an enlarged transverse vertical section on line 3—3 of Fig. 1.

Fig. 4 is an enlarged top plan view of certain of the structure shown in Fig. 1, and

Fig. 5 is a view similar to a part of Fig. 2 but with the contact plate in non-indicating position.

Referring to the drawing, I have shown a shuttle S such as shown in the aforesaid application having a split spindle 10 pivoted thereto as at 11. A detector lever 12 is movably mounted with respect to and supported by the spindle and has a detecting hump 13 normally urged by a spring 14 to move through a slot 15 in weft carrier C. The latter may be of any convenient form and has wound thereon a mass of weft W which normally covers the slot 15 and holds the hump 13 and detecting lever in depressed non-indicating position, as shown in Fig. 5. The detector lever is provided with a contact plate 16 movable therewith against which normally bears a lock pin 17 as shown in Fig. 5. The upper surface of the shuttle may be provided with a groove 18 which is aligned longitudinally with the contact plate.

When sufficient weft is present the plate 16 is held depressed with the pin 17 in its deflected position tending normally to move under a part of the plate. When the weft is exhausted the hump 13 moves upwardly through slot 15 under action of spring 14 to the position shown in Fig. 2 thereby raising the plate sufficiently to permit the lock pin 17 to spring thereunder as shown in Fig. 2. Means not necessary to the present disclosure operate to move the pin 17 back to its non-locking position whenever the spindle is raised to receive a fresh supply of weft.

It is to be understood that so far as the present invention is concerned the shuttle set forth is for purposes of illustration only and I do not wish to have the detector set forth in detail hereinafter restricted in its use to the specific form of shuttle described.

Fig. 1 shows the lay 20, lay end 21, spindle 22, and picker 23 propelled by picker stick 24. A shuttle box floor 25 is secured to the lay and a shuttle binder 26 may be provided to push the shuttle against the back wall 27 of the shuttle box by force derived from spring 28. A box top 29 has feet 30 through which securing bolts 31 extend into the lay and may extend above the box floor to complete the box.

The loom parts proper thus far described may be of the usual construction, the box top 29, however, being modified somewhat from usual

constructions for the purpose of supporting certain of the detecting parts to be set forth in detail hereinafter.

In carrying my invention into effect I form 5 the top 29 with a relatively large opening 40 having front and rear walls 41 and 42, respectively. A collector brush 43 is secured as at 44 to the box top and is therefore electrically grounded thereto, while a second collector brush 10 45 is mounted on a block of insulating material 46 to have connection with an electric conductor 47, the block being held rigidly in place on the box top as by a screw 48.

Extending across the opening 40 and through 15 both back and front walls is a stud 50 which may be of insulating material. This stud is mounted for limited vertical movement in elongated slots 51 and 52 which are in the walls 41 and 42, respectively. The stud is also provided 20 with a head 53 too large to pass through the opening 51, and a retaining clip 54, shown in Fig. 4 may be fixed to the box top or in any other manner so as to align with the head 53 and prevent loss or misplacement of the stud. 25 Mounted upon the stud are two roll contacts 60 and 61 each having a reduced hub 62 to have contact respectively, with the brushes 45 and 43. A washer of insulating material 63 is between the rolls, and that roll which corresponds to the 30 insulated brush is further insulated from the frame by a second washer 64 interposed between it and the frame or wall 41, as shown in Fig. 1.

In operation the brushes, which are preferably resilient, together with the weight of the 35 stud 50 and parts supported thereby, tend to hold the rolls in low position which is determined by the bottoms of the slots 51 and 52. As the shuttle is boxed the narrow rims 65 enter the slot 18 of the shuttle and the reduced hubs 40 62 roll along the top 66 of the shuttle. Under these conditions, assuming that sufficient weft is present, the contact plate will be below the rims 65, the rims extending beyond the hubs insufficiently to reach the depressed plate. Under 45 these conditions no electrical connection exists between the rolls.

When a depleted shuttle enters the box the 50 plate 16 will be elevated and near enough to the top of the shuttle to be engaged by the rims 65. The two rolls will therefore be brought into electric contact with each other so that an electric current can pass from the conductor 47 out through a circuit not shown but which is ultimately grounded, so that a return can be effected by brush 43. I have shown no particular 55 mechanism to be electromagnetically operated or controlled, inasmuch as the same forms no part of my present invention and any convenient contrivance of this type may be employed, such, 60 for instance, as that shown in my co-pending application Serial No. 665,140. The form of detector set forth herein is shown in the last named application but not claimed specifically therein.

65 As the shuttle moves under the rolls they will turn, either freely on the stud 50, or jointly therewith. In this respect I find it desirable to have a slight amount of looseness in the fit of the parts forming the detectors so that they may 70 easily and freely assume their correct detecting and indicating positions.

On all detecting operations there is likely to 75 be a vertical movement of the rolls due to and varying with the upward misplacement of the shuttle as it is boxed. The slots 51 and 52 are

high enough to provide for any such vertical motion as may be permitted by the box top 29. The bottom of the slots will usually be so proportioned with respect to the top of a properly placed shuttle as to hold the hubs above the shuttle rather than supported thereby. Under this arrangement a properly boxed shuttle will not contact with the rolls, but this is not an essential relation and I do not wish to be confined to it. To this extent therefore it should 10 be noted that the previously described operation of the rolls as the shuttle enters the box can be varied so as to avoid rotation of the rolls entirely when the shuttle is resting squarely on the bottom of the shuttle box. 15

As shown in Figs. 2 and 4 the stud 50 is in the left hand part of the slot 40, but I may provide an additional set of vertical slots indicated at 71 and 72 corresponding generally with slots 51 and 52 in the same walls, these additional slots being nearer the picker 23 so that when the latter becomes worn to such an extent as to permit deep boxing of the shuttle, the stud 50 and parts carried thereby can be moved to said additional slots to have the rolls more correctly placed with respect to the contact plate 16. The clip 54 is arranged for convenient removal to facilitate this alteration, and the brushes 43 and 45 are made sufficiently long to contact with the rolls when they are in any of 30 their possible correct positions.

From the foregoing it will be seen that I have provided a simple form of electric detector for shuttles operating with a plate arranged to have contact with the detectors when an indication of 35 weft exhaustion is to be given. The detectors, shown as rolls herein, are mounted for free limited vertical motion, and the dwell of the shuttle in the box between picks is of sufficient duration to assure proper contact between the rolls and 40 plate when an indication is desired. An inspection of Fig. 2 will show that the rolls are so placed that they can never have contact with the yarn or weft carried by the shuttle, inasmuch as the latter is brought to rest before the 45 zone occupied by the weft can move under the rolls. The free rotation of the contacting elements assures long life of the cooperating parts of the detecting mechanism and also provides for the presentation of a large number of contact surfaces to the plate 16. As the shuttle is picked out of the box its contact with the rolls will cause the latter to rotate by varying amounts as to cause a fresh part of the roll to be in contacting position with respect to the 50 plate on succeeding detecting beats of the lay. 55

Having thus described my invention it will be seen that changes and modifications may be made therein by those skilled in the art without departing from the spirit and scope of the 60 invention and I do not wish to be limited to the details herein disclosed, but what I claim is:

1. In a loom, a shuttle having a supply of weft, a pair of oppositely charged electric detector electrodes to be connected to effect a 65 change in loom operation, and a shuttle carried contact member for the electrodes held out of contacting relation with the electrodes when sufficient weft is present and movable relatively to the shuttle upon exhaustion of weft to a position to electrically connect said electrodes, said contact member being the only current carrying part permanently connected to the shuttle. 70

2. In a loom, a shuttle carrying a mass of weft, a pair of oppositely charged electric de- 75

- 5 tector electrodes to be connected to effect a change in loom operation, a shuttle carried contact member for the electrodes normally out of contacting relation with the latter when sufficient weft is present, and means operatively related to the contact member and under the control of the mass of weft and effective at weft exhaustion to move said contact member to a position to electrically connect the electrodes by direct engagement therewith, the contact member being the only part permanently carried by the shuttle which conducts current. 10
- 10 3. In a loom, a shuttle, a pair of oppositely charged electric detector electrodes to be connected to effect a change in loom operation, a spindle therefor, a detector element pivoted to the spindle and having a detecting surface to engage the interior of a mass of weft carried by the spindle, and a contact member carried by and movable with the detector element, sufficient 15 weft engaging the detector element to hold the contact member out of engagement with the electrodes, said contact member movable at exhaustion of weft to electrically connect said electrodes by direct engagement therewith. 20
- 20 4. In a loom, a shuttle, a pair of oppositely charged electric detector electrodes to be connected to effect a change in loom operation, a spindle having a tip, a pivotal connection between the spindle and the shuttle, a detector element pivoted to the spindle between the tip 25 and the interior of the mass of weft to hold said contact member on the detector element extending to a position over the pivotal connection, a detecting surface for the element to engage the interior of the mass of weft to hold said contact member in a relatively low position, and yielding means effective to move the contact member into direct engagement with the electrodes at exhaustion of weft to electrically connect said electrodes. 30
- 30 5. In a loom, a shuttle having a supply of weft, a pair of oppositely charged electric detector electrodes to be connected to effect a change in loom operation, a shuttle carried contact member for the electrodes held out of contacting relation with the electrodes when sufficient weft is present and movable relatively to the shuttle upon exhaustion of weft to a position to electrically connect said electrodes by direct engagement therewith, the electrodes movable toward the contact member, and means to limit movement of one of the electrodes toward the contact plate. 35
- 35 6. In a loom, a shuttle having a supply of weft, a pair of oppositely charged electric detector electrodes to be connected electrically to effect a change in loom operation, a contact member for the electrodes held out of contacting relation with the electrodes when sufficient weft is present and movable relatively to the shuttle upon exhaustion of weft to a position to electrically connect said electrodes, and means carried by one of the electrodes to engage the shuttle to limit movement of said electrode toward the member. 40
- 40 7. In a loom, a shuttle having a supply of weft, a pair of oppositely charged electric detector elements to be connected electrically to effect a change in the operation of the loom, a contact member for the elements held out of contacting relation with the elements when sufficient weft is present and movable relatively to the shuttle upon exhaustion of weft to a position to electrically connect said elements, said contact member being the only current carrying part permanently connected to the shuttle, and the electrodes positioned to engage the contact member at points spaced transversely of the shuttle. 45
- 5 8. In weft detecting mechanism for a loom operating with a shuttle having an electric current conducting plate, a pair of rolls of opposite electric polarity, an insulating support for said rolls, means to mount said support to position the rolls over the plate when the shuttle is boxed, and means defining vertical guides for the insulating support whereby the rolls have limited vertical movement under impact of a misplaced shuttle. 50
- 15 9. In weft detecting mechanism for a loom operating with a shuttle having an electric current conducting plate, a shuttle box including a box top, a pair of detector rolls of opposite electric polarity, and means to support the rolls with respect to the box top to position said rolls for engagement with the plate on the shuttle when the latter is in the box. 55
- 25 10. In weft detecting mechanism for a loom operating with a shuttle having an electric current conducting plate, a shuttle box including a box top, a pair of detector rolls of opposite electric polarity, means to support the rolls with respect to the box top to position said rolls for engagement with the plate on the shuttle when the latter is in the box, and means to provide for mounting the rolls in a plurality of positions longitudinally of the length of the box to effect registry of the rolls with respect to said plate for different positions of the shuttle in the box. 60
- 35 11. In weft detecting mechanism for a loom operating with a shuttle having an electric current conducting plate, a shuttle box including a box top, a pair of insulated rolls of opposite electric polarity, means to support the rolls with respect to the box top to position said rolls for engagement with the plate on the shuttle when the latter is in the box, and a pair of brushes supported by the box top for the rolls. 65
- 45 12. In weft detecting mechanism for a loom operating with a shuttle having an electric current conducting plate, said shuttle having a slot extending longitudinally thereof in registry with the plate, and a pair of insulated rolls of opposite electric polarity mounted to have portions thereof enter the slot to be positioned for engagement with the plate when exhaustion is to be indicated. 55
- 50 13. In weft detecting mechanism for a loom having a shuttle box to receive a shuttle having a plate of electric conducting material, a pair of roller contacts mounted on the top of the box to have engagement with the plate when indication of exhaustion is to be given, and a picker to move the shuttle out of the box movable under the rolls. 60
